44. *ORNAMENT*

UNITED STATES PATENT OFFICE.

JAMES F. SWATZELL, OF DECATUR, ALABAMA.

PORTABLE CYLINDER REBORING AND REGRINDING MACHINE.

1,418,744.

Specification of Letters Patent. Patented June 6, 1922.

Application filed August 16, 1919. Ser. 1 No. 318,281.

To all whom it may concern:

Be it known that I, JAMES F. SWATZELL, a citizen of the United States of America, residing at Decatur, in the county of Morgan and State of Alabama, have invented certain new and useful Improvements in Portable Cylinder Reboring and Regrinding Machines, of which the following is a specification.

10 My invention relates to a portable reboring and regrinding machine especially adapted for work on automobile cylinders without requiring their removal from their bases, though certain features of my invention are 15 available for all types of boring and grinding machinery. My invention is characterized by the provision of a novel drive means adapted for the ready interchangeability of boring or grinding tools, and by the use of 20 a motor mounted on top of and movable with the tool carriage to simplify the feeding and driving of the boring or grinding tool.

25 My invention also comprises the novel details of construction and arrangements of parts, which in their preferred embodiment only are illustrated in the accompanying drawings, in which:—

Fig. 1 presents in vertical sectional elevation my apparatus equipped with a regrinding tool.

Fig. 2 illustrates the motor driving shaft with the grinding wheel shaft disconnected therefrom.

35 Fig. 3 illustrates the reboring tool interchangeable for the regrinding tool shown in operating position in Fig. 1.

Figs. 4 and 5 are cross sectional views taken on the lines 4—4 and 5—5 of Fig. 1.

40 Fig. 6 is an enlarged plan view of the interlocked eccentric sleeves set to revolve the regrinding tool about a circle having a larger radius than the sleeves.

Fig. 7 is a view illustrating a modified 45 means for locking of the eccentric sleeves.

Similar reference numerals refer to similar parts throughout the drawings.

In the preferred embodiment of my invention, I provide a base plate 1 having 50 therein a circular tool opening 2 and marginal bolt holes 3 adapted to receive clamping bolts which pass through the bolt holes in the top of the cylinder to be worked over.

55 At one side of this plate I attach in any manner an upright frame 4 comprising a pair of

spaced vertical slide guides 5 which are reinforced by webs 6. These slide guides are undercut in their outer faces and are adapted to be engaged by correspondingly undercut tongues 7 on the vertically movable carriage 8. Preferably one of the tongues 7 is narrower than the other to provide for the insertion of a wear strip 9 held against the guide by a series of set screws 10, thus making provision for the wear in the slide ways. 65 The slide guides 5 are connected overhead by an out-turned flange 11 which in its overhanging portion is provided with a vertical hole to receive the upper end of the carriage feed screw 12, which screw has a collar 13 70 engaging the under face of the flange 11 above which its upper end projects sufficiently to pass through the base of an angle bracket 14 and a bevelled gear 15 to receive a clamp nut 16 which is normally set tight 75 so as to hold the screw 12 rigidly against rotation. The lower end of the screw is left free and at an intermediate point it has threaded thereon a sleeve nut 17 having a worm wheel 18 formed integral with or fast 80 on its upper end and having the lower end of its sleeve-like body externally threaded to receive a nut 19. The sleeve body of the nut turns on a bearing in an out-turned bracket 20 on the carriage 8, which bracket 85 is preferably disposed substantially above the main body portion of the carriage for purposes which will be later apparent.

At its outer end this bracket 20 carries a bearing 21 in which turns the outer end of a 90 countershaft 22 which is driven by the motor shaft 23. The motor 24, as illustrated, is of the electric type, but is typical of any suitable type of motor. The motor is supported by brackets 25 and 26, the first being made fast 95 to the carriage bracket 20 and the latter being bolted to spaced sleeve bearings 28 on the carriage. The motor is thus rigidly mounted on and movable with the carriage. The motor shaft 23 is provided with a worm gear 29 100 which meshes with a worm wheel 30 on the countershaft 22 and this countershaft, as shown in Fig. 4, is provided with two worm gears 31 and 32, the former meshing with a worm wheel 33 fast on a vertical shaft 34 and 105 the latter meshing with the worm wheel 18 on the sleeve nut 17. The shaft 34 is mounted overhead in a bearing bracket 35 attached to the motor bracket 25 and below it turns in a step bearing in the carriage bearing 28. Near 110

its lower end the shaft 34 carries a gear wheel 36 which meshes with a gear 37 fast on or integral with the outer driving sleeve 38 which is provided with an eccentric bore in 5 which an inner sleeve 39 turns with a close fit and this sleeve 39 is likewise provided with an eccentric bore. The outer sleeve 38 is mounted to turn in bushes in the carriage 10 bearings 28, the lower end of the sleeve 38 being externally threaded to receive a nut 40 which in conjunction with the gear 37 holds the sleeve in position in said bearings. The lower end of the inner sleeve 39 is provided with a flange 41 which engages the under face of the nut 40 and the lower end of the sleeve 38, while the upper end of the sleeve 39 is externally threaded to receive a clamp 42 which engages the top face of the gear 37 on the outer sleeve 38. By tightening 15 the nut 42 the two sleeves are clamped in the desired relative position. Through the bore in the inner sleeve 39 I pass a drive shaft 43 which is intended to produce a fast spinning drive for the grinding wheel. This shaft 43 is provided with a pair of universal joints 44 which are typically illustrated but which may be of any standard construction. The shaft at its upper end is provided with a socket 45 adapted to receive the squared lower end 46 of the motor shaft and to be made fast thereto by a set screw. The lower end of the shaft 43 is threaded and adapted to screw into the upper end of the emery wheel spindle 47, which spindle is mounted to turn 20 in an emery wheel arbor 48, the spindle having a collar 49 at its upper end and at its lower end being threaded to receive a screw 50 by which the emery wheel clamping collar 51 is pressed against the emery wheel 52 to hold it in position between said collar and an upper collar 53 fast on the spindle. The spindle at its upper end turns in a bushing 54 in the arbor which has its bore enlarged throughout the major portion of its length 25 and at its lower end is provided with two anti-friction bearings 55 in which the lower end of the spindle turns. The cavity in the arbor is filled in any suitable manner with lubricant for the spindle bearing. The arbor 30 at its lower end bears against the fixed collar 53 on the spindle and at its upper end the arbor is provided with a collar nut 56 and with a reduced threaded shank 57 which is adapted to screw into the lower threaded end of the 35 bore in the inner sleeve 39.

When a boring bar 58 is to be substituted for the emery wheel arbor 48, the latter is unscrewed from the sleeve 39, the set screw having first been loosened to disconnect the 40 shaft 43 from the motor shaft 23 and the arbor 48 and shaft 43 are thus detached as a whole from the apparatus. The boring bar 58 is then mounted in position, its threaded shank 59, corresponding to 57 on the emery 45 wheel arbor, being screwed into the sleeve

39. A tool disk 60 is attached in the customary manner on the lower end of the boring bar.

For raising the carriage by hand I provide a hand crank 61 fast on a shaft 62 which is 70 mounted to turn in the vertical leg of the bearing bracket 14. This shaft carries a bevelled gear 63 which meshes with the gear 15. To use the crank it is necessary first to loosen the nut 16 so that the screw 12 is free 75 to turn.

In Fig. 7 I illustrate an arrangement for adjusting the sleeves 38 and 39 by the provision in the former of an elongated slot 64 through which a screw stud 65 passes and is 80 screwed into the inner sleeve 39. A lock nut 66 is screwed on the outer end of the stud 65 and engages a concave washer 67 which bears against the outer convex surface of the sleeve. This washer is provided with a pointer 68 85 which works over a micrometer gauge 69 on the outer sleeve. By loosening up the nut, and at the same time loosening the sleeves, the inner sleeve can be adjusted by the stud to the desired extent relative to the outer 90 sleeve and by reference to said gauge so as to give the exact diameter desired to the path of revolution of the grinding wheel. In addition thereto the stud and nut form an added clamping means for holding the 95 sleeves in set position.

When the stud 65 is adjusted to zero position on the micrometer gauge the boring bar or the grinding arbor will be concentric with the motor shaft and sleeves. As the 100 stud is shifted over gauge the center of the arbor moves to positions increasingly eccentric to the drive shaft and sleeve centers. When the boring bar is in service the sleeves must be in position to bring the boring bar concentric with the sleeves. To insert the grinding arbor, the boring bar is unscrewed from the inner sleeve and the grinding arbor is substituted, the shaft 47 being inserted upwardly through the sleeve and 105 connected to the motor shaft and at the same time the arbor is screwed into the inner sleeve. The sleeves may then be relatively adjusted to give the rapidly rotating grinding wheel the desired path of revolution according to the diameter of the cylinder to be ground and as the grinding proceeds the sleeve nut 17 is constantly turned 110 so as to feed the carriage downwardly until the whole cylinder is reground, after which 115 the current in the motor can be reversed or the nut 16 on the screw is loosened and the screw itself rotated by the hand crank so as to bring the nut back up with the carriage.

I consider the two telescoping sleeves as the preferred means for obtaining the eccentric adjustments of the grinding wheel, but my invention contemplates the combination of any equivalent rotating means capable of 120

shifting the point of connection of the boring arbor eccentrically with relation to the projected center line of the driving element.

This invention is not intended to be restricted in scope to the specific embodiments shown, but contemplates such modifications as come within the spirit and scope of the claims.

What I claim as new and desire to secure 10 by Letters Patent, is:-

1. In a portable cylinder reboring and grinding machine, a base having suitable means for being mounted on a cylinder to be bored, a vertical guide on said base, a carriage vertically adjustable on said guide, a sleeve eccentrically bored which is journaled in the carriage with its axis concentric with the cylinder to be bored, a sleeve eccentrically bored which is rotatable in said first mentioned sleeve, end fastenings to hold said sleeves in fixed relative position, a gear rigid with the outer sleeve, an electric motor mounted on the top of the carriage with the
- axis of its driving shaft concentric with the cylinder to be bored, a worm on said motor shaft, a feed for the carriage having a driving transmission comprising a worm shaft and a worm wheel driven by said worm, a flexible shaft extending through the inner of said sleeves and having a detachable connection with the lower end of the motor shaft, a worm gearing driven from said worm shaft and comprising a pinion meshing the gear on the outer sleeve, and means to detachably connect a tool shank to the lower end of the inner sleeve.
2. A portable cylinder reboring and grinding apparatus in accordance with claim 1, in which the tool shank is hollow and has journaled therein a grinding tool shaft, adapted to be coupled to said flexible shaft.

In testimony whereof, I affix my signature.

JAMES F. SWATZELL.
